ADJUSTABLE BROOCH OR SIMILAR ARTICLE

Marcel Boucher, Eltingeville, N. Y.

Application July 10, 1953, Serial No. 25,866

Term of patent 7 years

(Cl. D45—19)

To all whom it may concern:

Be it known that I, Marcel Boucher, a citizen of the United States, residing at Eltingeville, in the county of Richmond and State of New York, have invented a new, original, and ornamental Design for an Adjustable Brooch or Similar Article, of which the following is a specification, reference being had to the accompanying drawing forming part thereof.

In the drawing:

Fig. 1 is a front view of an adjustable brooch or similar article, showing my new design.

Fig. 2 is a top view of the brooch.

Fig. 3 is a side view thereof.

Fig. 4 is a front elevation of the adjustable brooch illustrating said brooch in a different position from that shown in Fig. 1.

I claim:

The ornamental design for an adjustable brooch or similar article, as shown.

MARCEL BOUCHER.
